UNITED STATES PATENT OFFICE

2,314,579

WIRE OR ROD CONNECTOR

Louis Frank, Taft, Calif.

Application July 23, 1941, Serial No. 403,602

10 Claims. (Cl. 287—76)

My invention relates to a connector for wires, rods, cables, tubes, and the like, and the particular construction herein described and claimed is an improvement on the wire or rod connector covered by U. S. Letters Patent No. 2,187,230 issued January 16, 1940, also the wire or rod connector set forth in my application for U. S. Letters Patent filed May 25, 1938, Serial No. 209,955.

The principal objects of my present invention are, to generally improve upon and simplify the form of the connectors disclosed in my aforesaid patent and pending patent application, as well as other existing forms of similar rod and wire connecting devices, and further, to provide a relatively simple, practical and inexpensive connector which is constructed so as to effectively perform its clamping and connecting functions without the requirement of screws, bolts, binding posts, and the like, that include exposed and projecting binding or connecting elements.

Further objects of my invention are, to provide a wire or rod connector of the character referred to that may be utilized for effectively gripping and connecting the ends of wires, rods, tubes, or the like, that occupy angular positions with respect to each other, and to construct the connector so that they may be adjusted for use as a Y connector or as a cross connection, and which arrangement is particularly advantageous wherever a connection is made between the wires of a main current supply line and two or more branch current distributing wires.

A further object of my invention is, to provide in a connector of the character referred to simple and efficient means for regulating the tension of the springs associated with the wire or rod gripping jaws and consequently regulating the degree of gripping pressure between said jaws and the engaged rods or wires.

Further objects of my invention are, to provide a wire or rod connector that is of strong, substantial structure, capable of being readily assembled or taken apart so as to facilitate inspection and replacement or interchange of parts, and likewise capable of being easily and quickly applied to or removed from the adjacent ends of wires, rods, or the like.

With the foregoing and other objects in view, my invention consists in certain novel features of construction and arrangement of parts that will be hereinafter more fully described and claimed and illustrated in the accompanying drawings in which:

Fig. 1 is a longitudinal section taken through

the center of a wire or rod connector constructed in accordance with my invention.

Fig. 2 is a cross section taken on the line 2—2 of Fig. 1.

5 Fig. 3 is a longitudinal section taken through the center of one of the nuts used on the ends of the connector.

Fig. 4 is a longitudinal view of a device constructed in accordance with my invention and 10 utilized as a rod or wire gripping member.

Fig. 5 is a longitudinal section taken through the center of a modified form of the nut that is mounted on the end of the connector.

15 Fig. 6 is a cross section taken on the line 6—6 of Fig. 5.

Fig. 7 is a sectional view taken lengthwise through the center of a modified form of a wire or rod clamping member constructed in accordance with my invention.

20 Fig. 8 is a cross section taken on the line 8—8 of Fig. 7.

Fig. 9 is a perspective view of one of the wire or rod engaging jaws utilized in the form of clamp illustrated in Fig. 7.

25 Fig. 10 is a vertical section taken through the center of the form of nut that is utilized in connection with gripping jaws of the type illustrated in Fig. 9.

Fig. 11 is a detail sectional view showing a 30 modified form of the wire or rod gripping members.

Fig. 12 is a perspective view of one of the modified forms of wire gripping members.

Fig. 13 is a detail view showing a further modified form of the wire or rod gripping means.

Fig. 14 is a longitudinal section taken through the center of the form of connector utilized for connecting rods or wires that occupy angular positions with respect to each other.

40 Fig. 15 is a plan view of a three-way connector constructed in accordance with my invention.

Fig. 16 is a plan view of a four-way wire or rod connector.

Fig. 17 is an enlarged cross section taken on 45 the line 17—17 of Fig. 15.

Fig. 18 is a longitudinal section taken through the center of a modified form of the wire or rod gripping element.

50 Figs. 19 to 22 inclusive are elevational views of modified forms of wire gripping members that may be used in my improved connector.

Referring by numerals to the accompanying drawings and particularly the construction illustrated in Figs. 1, 2, and 3, 10 designates the main body of the connector, which body comprises

substantially tubular members 11 and 12 with the outer end portions of the openings through said members gradually tapering toward their outer ends as designated by 15.

The inner ends of the body members 11 and 12 are detachably connected by interengaging screw threads as designated by 14. Arranged to move freely within the tubular members 11 and 12 are substantially tubular members 16 and 17 respectively, the same provided intermediate their ends with tapered portions, the inclination of which corresponds with the tapered end portions 15 of the members 11 and 12.

Formed through the tapered portions of the walls of members 16 and 17 are apertures 18 and loosely seated therein are small hard metal balls 19 that are adapted to engage the tapered surfaces 15 of members 11 and 12. Thus as the members 16 and 17 are moved outwardly away from each other within the body members 11 and 12 under the influence of an expansive spring 20 that is interposed between the inner ends of members 16 and 17, the balls 19 bearing on the inclined surfaces 15 will be moved inward to engage and grip wires, rods, or the like, that are inserted in tubular members 16 and 17. The inner ends of the apertures 18 are slightly smaller in diameter than the outer ends thereof, thus preventing the balls 19 from passing inwardly through said apertures.

Mounted on the outer end portions of the body members 11 and 12 are nuts 21 provided with outer end walls 22 having centrally arranged openings 23 for the accommodation of the outer ends of the tubular members 16 and 17, and these nuts are provided with internal threads 27 which engage diametrically opposite lugs 29 formed on the ends of the members 11 and 12.

In order to facilitate quick adjustment of the nuts on the ends of the body members, the internal threads 27 are interrupted by longitudinally disposed channels 28 for the accommodation of the lugs 29. The edges of the end walls 22 around the central openings therein fit loosely within grooves 24 that are formed in the outer end portions of members 16 and 17 and the end portions of said last mentioned members beyond said grooves are flanged outwardly as designated by 26, and which arrangement permits the nuts to rotate freely on the outer end portions of the members 16 and 17 and to connect said nuts with said members so that the same move longitudinally together.

To connect the ends of a pair of wires, rods, or the like, with the connector just described, the end portions of said wires are inserted into the tubular members 16 and 17, which latter have been moved inward toward each other against the resistance offered by expansive spring 20, such action being accomplished by screwing the nuts 21 onto the end portions of the body members 11 and 12, and after the inserted portions of the wires or rods pass the balls 19 and move the same outward the nuts are partially unscrewed from the ends of body members 11 and 12, which action draws the tubes 16 and 17 outwardly so that the balls 19 engaging the inclined surfaces 15 will be moved radially inward so as to grip and clamp the inserted wires.

The nuts 21 may be adjusted on the ends of the body members 11 and 12 so as to compensate for the tension of the spring 20 between the members 16 and 17 and such adjustment also compensates for the varying sizes or diam-

eters of the wires or rods that are engaged and clamped by the connector.

The construction illustrated in Fig. 4 is designed to be applied to and clamp on the end of a rod or wire and in this construction a tubular member 30 has one end closed by a removable plug or cap 31. A portion of the opening through member 30 opposite the end that is closed by the plug tapers gradually toward its outer end as designated by 32 and arranged for sliding movement in member 30 is a tube 33 provided on its inner end with an extension 34 of reduced diameter. Interposed between the plug 31 and the shoulder between the reduced portion 34 and the body of the tube 33 is an expansive spring 35.

Formed through the wall of the tube 33 opposite the tapered portion 32 of member 30 is a series of apertures 36 in which are located small balls 37 of hardened metal and which directly engage and grip the inserted ends of wires, rods, or the like, W.

A cap nut 38 provided with an internal thread 39 is mounted to rotate freely upon and to move longitudinally with the end of tube 33 that projects beyond the end of tubular body 30 and the thread of this nut is adapted to engage diametrically opposite lugs 39a that are formed on the end of the body member 30. The internal thread of nut 38 is intersected by a pair of diametrically opposite longitudinally disposed grooves 40 for the accommodation of the lugs 39a, thus permitting the nut and the tube 33 carried thereby to be quickly adjusted longitudinally before being finally adjusted as a result of the engagement of thread 39 with lugs 39a.

In this construction, the end of a wire or rod W is inserted in tube 33, which latter has been adjusted longitudinally within the end of tubular body 30 by manipulation of the nut 38, such adjustment being made to compensate for the tension of the spring 35 and for the size of the inserted wire or rod and when so inserted the rod is engaged and gripped by the balls 37 that move inwardly as to ride down the tapered surface 32 of member 30.

In Figs. 5 and 6 I have illustrated a modified construction wherein a cap 41 which corresponds to the nuts 21 and 38, is provided on its inner end with lugs 42 that engage screw threads 43, the latter being formed on the end of the body of the connector, for instance, either one of the members 11 and 12 or member 30. The thread 43 is intersected by longitudinally disposed grooves 44 for the accommodation of the lugs 42, thus enabling quick adjustment of the cap on the threaded end of the body.

In this construction, 45 designates the end of the tubular member that carries the wire or rod gripping balls, the end of which member is mounted for rotation in the end wall of cap 41 and the end of said member 45 being flanged outwardly as designated by 46 so that the cap and tubular member 45 move longitudinally together.

The nuts 21 and 38 in addition to providing means for regulating the tension of the springs 20 and 35 and for the positioning of the tubular members 17 and 33 in the body members 10 and 30, may be utilized, by screwing them inwardly onto the ends of the body, for moving the tubular members 17 and 33 inwardly, thereby breaking the gripping engagement between the balls 19 and 37 and the inserted rods

or wires, and which action is particularly desirable in the event that there is any tendency of the balls to stick to the engaged wires or rods after long periods of service.

The modified construction illustrated in Figs. 7, 8, and 9 is designed as a clamp to be applied to the end of a wire or rod, and said clamping member includes a substantially tubular body 47 and the opening therethrough is provided adjacent one end with a tapered portion 48.

Formed in the outer surface of the end of tube 47 beyond the tapered inner portion are diametrically opposite recesses 49. The opposite end of tubular member 47 is closed by a screw plug or cap such as 47a. Interposed between the plug 47a and shoulders 51a that are formed on a pair of jaws 51 is an expansive spring 50. Each jaw 51 is substantially half round in cross section and formed on the inner flat face of each jaw is a longitudinally disposed groove that is provided with transversely disposed teeth or corrugations 53.

One end of the body of each jaw 51 is provided with a tapered portion 48a that is adapted to engage a correspondingly tapered portion 48 in the opening through tubular body 47. Extending from the tapered end portion of the body of each jaw is a channel-shaped member 52 and formed on the end thereof is an externally arranged rearwardly projecting flange 55.

The flanges 55 on the jaws 51 occupy an annular groove 54 that is formed within a nut 58, the same being provided on its inner end with inwardly projecting lugs 57 that are arranged for longitudinal sliding movement in the recesses 49 in the end of body 47. An internal flange 56 formed on nut 58 interengages the flanges 55 on the outer ends of the jaws 51 and thus as said nut is moved inwardly relative to the tubular body 47, jaws 51 will likewise be moved inwardly against the resistance offered by spring 50 and which action will disengage the teeth 53 on the jaws from the inserted wire or rod.

When the clamp is applied to a wire, rod, or the like, the latter is inserted lengthwise between the jaws and the spring 50 under tension acts to force the jaws outwardly so that the teeth 53 on said jaws will engage and grip the wire or rod.

In Fig. 10 I have shown the nut used on the form of clamp illustrated in Fig. 7 as constructed with a main body portion 58 provided with the annular groove 54 and flange 56 and with a secondary part 58a that is rigidly secured by welding or otherwise in a recess in the outer face of the body 58. Such construction enables the nut to be readily assembled with the flanges 55 on the outer ends of the jaws 51.

In Figs. 11 and 12 I have shown a modified form of the rod gripping elements that are carried by the tubes 17 and 33. In this construction a tube 60 which corresponds with either tube 17 or 33 is provided in its wall with an opening 64, the outer end thereof being enlarged to form an annular groove 65, and loosely arranged in said aperture is a substantially hemispherical rod gripping member 66 provided on its flat side with a flange 67 that is loosely seated in groove 65. The face of the member 66 outwardly from the flange 67 is made slightly convex as designated by 68, for engagement with the inclined face 62 of the tubular member 61 that surrounds tubular member 60.

Thus as member 60 moves outwardly in member 61, the gripping member 66 is forced in-

wardly as a result of engagement with the tapered surface 62, thereby gripping the wire or rod that is positioned in tubular member 60.

In Fig. 13 I have shown a modified form of the members 17 and 33 that carry the rod gripping balls 19, such modified construction including a tubular member 17a having a tapered portion 17b, and formed through the wall of said tapered portion are apertures 17c which receive rod gripping balls 17d of different diameters and which balls engage against the tapered surface formed on the tubular body that surrounds the member 17a.

The modified constructions illustrated in Figs. 14, 15, and 16 are designed for connecting wires or rods that are disposed in angular relationship and also for connecting three or four rods or wires and which provision is particularly advantageous where it is desired to connect a plurality of branch wires to a main electric current supply line.

In the construction illustrated in Fig. 14, the inner ends of tubular members 70 and which receive the sliding members 71 that carry the rod gripping members 72 are provided with overlapping extensions 73, through the centers of which pass a pivot member 74 such as a rivet or bolt. Such construction enables either member 70 to be shifted into different angular positions with respect to each other throughout an arc of approximately three hundred twenty degrees and which arrangement is especially desirable where the wires or rods that are to be connected occupy acute angular positions with respect to each other.

In Fig. 15 I have illustrated three wire or rod gripping members 75 connected to each other by a pivotal member 76 such as a rivet or bolt, thus enabling all of the members to be shifted into different angular positions as illustrated by dotted lines in said figure.

In Fig. 16 I have illustrated four of the gripping members 77 connected to a common pivot 78 such as a rivet or bolt.

In Fig. 17 I have illustrated in cross section a tubular body 79 corresponding to the bodies 12 and 30 previously described, with a nut 80 corresponding to the nuts 21 and 38 previously described located upon its end, and with a tubular member 81 which corresponds to the members 17 and 33 previously described, extending lengthwise through the body member 79. This construction is particularly designed for use in connecting rods and wires of large diameters and in order to firmly grip said wires or rods, three hemi-spherical gripping members 82 similar to the members 66 previously described are loosely arranged in apertures 83 that are formed in the member 81.

To further increase the gripping engagement between the members 82 and the inserted rod or wire W, the central portions of the convex faces of the members 81 are knurled as designated by 84.

In Fig. 18 I have illustrated a tubular member 85 that corresponds with members 17 and 18 previously described and formed in the tapered portion of said member 85 are pairs of apertures 86 disposed longitudinally of the member 85, which apertures receive hemi-spherical rod gripping members 87, which have the same diameter but of different lengths, the latter condition due to the fact that the thickness of the wall in which the apertures 86 are formed gradually decreases toward the outer end of member 85 and

consequently the forward openings are shorter than those to the rear.

In Figs. 19 to 21 inclusive, I have illustrated a series of substantially hemi-spherical rod gripping member 88, each provided on its base or flat side with a flange 89, all of the flanges being of the same diameter but the bodies being of different lengths so as to conform with the lengths of the openings in the tubular member that carries said rod gripping members. A portion of the face of each member 88 is knurled or corrugated as designated by 90 in order to increase the gripping effect of the members on the inserted wire or rod.

In Fig. 22 I have shown a rod or wire gripping ball 94, the entire surface of which is knurled in order to increase its gripping effect.

Inasmuch as the wire or rod gripping members such as 19, 37, and 66 have a certain amount of radial movement relative to the axis of the connector, the latter may be used for connecting wires, rods, and the like, of different diameters, and as illustrated in Figs. 13 and 16 the tubular members into which the rods or wires are inserted may carry a plurality of sets of two, three, or more wire or rod gripping members.

The various parts of my improved connector and clamp and particularly the external parts thereof may be formed of suitable insulating material or the external parts may be provided with coatings of insulation, thus eliminating the possibility of electric shocks and possible injury to the users of the connector while placing the same on current carrying wires.

My invention contemplates the connector constructed so as to utilize one, two or more of the rod gripping members as illustrated in Figs. 12 and 19 to 22 inclusive and said rod gripping members may be substantially hemi-spherical in shape as illustrated in Figs. 12 and 20, substantially conical in shape as illustrated in Fig. 19, or substantially spherical as illustrated in Fig. 22. Further, the surfaces of said gripping members that engage the connected wires or rods may be smooth as illustrated in Figs. 12 and 13, partially knurled as illustrated in Figs. 19 to 21 inclusive, or fully knurled as illustrated in Fig. 22.

While I have shown the connector as being particularly adapted for connecting wires, rods, or the like, that are round in cross section, it will be understood that said connectors may be formed so as to connect wires or rods that are square or polygonal in cross section.

By utilizing spherical rod gripping members of different sizes or by using rod gripping members of different lengths as illustrated in Figs. 19 to 21 inclusive, the same connector comprising the tubular housing and the tubular member that is mounted for longitudinal movement within said housing may be utilized for the effective coupling of wires or rods of different diameters.

Thus it will be seen that I have provided a wire or rod connector that is relatively simple in construction, inexpensive of manufacture, and very effective in performing the functions for which it is intended.

It will be understood that minor changes in the size, form and construction of the various parts of my improved wire or rod connector, may be made and substituted for those herein shown and described, without departing from the spirit of my invention, the scope of which is set forth in the appended claims.

I claim as my invention:

1. In a wire or rod connector, a housing, a tu-

bular member arranged for longitudinal movement within said housing, one end of which tubular member projects beyond the corresponding end of the housing, a spring for yieldingly resisting the movement of the tubular member into the housing, gripping members loosely carried by said tubular member, said housing being provided with internally arranged inclined surfaces against which said gripping members engage as they move outwardly with said tubular member, a member loosely mounted upon the projecting end of said tubular member and engaging the adjacent end of the housing for moving said tubular member in both directions through said housing and means on the outer end of said tubular member for limiting the outward movement of said loosely mounted member thereupon.

2. In a wire or rod connector, a housing, a nut screw seated on one end of said housing, a tubular member arranged for sliding movement in said housing and having one end extending loosely through said nut screw, means on the end of said tubular member for limiting the outward movement of the nut thereupon, an expansive spring within said housing behind said tubular member, wire or rod gripping members loosely carried by said tubular member and there being inclined surfaces formed within said housing against which said gripping members engage as they move outwardly with said tubular member.

3. In a wire or rod connector, a housing provided adjacent its ends with internally arranged inclined surfaces, tubular members arranged for sliding movement through the end portions of said housing, an expansive spring arranged between the inner ends of said tubular members, rod gripping members loosely carried by said tubular members and adapted to engage the inclined surfaces within the housing as said tubular members move outwardly, means carried by the outer ends of said tubular members and engaging the ends of the housing for moving said tubular members in both directions through said housing and means on the outer ends of said tubular members for limiting the outward movement of said tubular member moving means.

4. In a wire or rod connector, a housing provided adjacent its ends with internally arranged inclined surfaces, tubular members arranged for sliding movement through the end portions of said housing, an expansive spring arranged between the inner ends of said tubular members, rod gripping members loosely carried by said tubular members and adapted to engage the inclined surfaces within the housing as said tubular members move outwardly, nuts loosely mounted on the projecting ends of said tubular members, which nuts have threaded engagement with the ends of said housing and stops formed on the outer ends of said tubular members for retaining the nuts thereupon.

5. In a wire or rod connector, a housing provided adjacent its ends with internally arranged inclined surfaces, tubular members arranged for sliding movement through the end portions of said housing, an expansive spring arranged between the inner ends of said tubular members, rod gripping members loosely carried by said tubular members and adapted to engage the inclined surfaces within the housing as said tubular members move outwardly, manually operable means mounted for rotation on the projecting ends of said tubular members and having longitudinal sliding engagement with said housing for moving said tubular members and the rod

gripping members carried thereby longitudinally through the end portions of said housing and stops on the outer portions of said tubular members for limiting the outward movement of the manually operable means mounted thereupon.

6. In a wire or rod connector, a plurality of housings, means pivotally connecting said housings whereby the same may be swung into different angular positions, means arranged for longitudinal movement in each housing for clamping an inserted rod or wire, means carried by the outer end of each clamping means and cooperating with the adjacent housing for moving said clamping means longitudinally with respect to said housing and stops formed on the outer portions of said clamping means for engaging and limiting the outward movement of said clamping means moving means.

7. In a wire or rod connector, a housing provided with an internally arranged tapered surface, a tubular member arranged for sliding

movement within said housing, the wall of which tubular member is provided with a tapered portion, there being apertures formed in the tapered portion of said tubular member and substantially

5 hemi-spherical rod gripping members loosely arranged within said apertures and adapted to engage the tapered surface within said housing as said tubular member moves outwardly with respect to said housing.

10 8. A wire or rod connector as set forth in claim 7 and flanges on the flat end portions of said rod gripping members.

9. A wire or rod connector as set forth in claim 7 and which rod gripping members differ in 15 lengths and have substantially the same diameters.

10. A wire or rod connector as set forth in claim 7 and the convex surfaces of said rod gripping members being knurled.

LOUIS FRANK.
